UNITED STATES PATENT OFFICE.

PETER F. WHITE AND WALTER GRANT, OF McNEIL ISLAND, WASHINGTON.

TOOTH-BRUSH.

1,091,993.

Specification of Letters Patent. Patented Mar. 31, 1914.

Application filed August 9, 1912. Serial No. 714,264.

To all whom it may concern:

Be it known that we, PETER F. WHITE and WALTER GRANT, citizens of the United States, residing at McNeil Island, in the county of Pierce, State of Washington, have invented certain new and useful Improvements in Tooth-Brushes; and we do hereby declare the following to be a full, clear, and exact description of the invention, such as will enable others skilled in the art to which it appertains to make and use the same.

This invention has special reference to tooth brushes and more particularly to an improved sanitary tooth brush which embraces a handle forming tool and a separable brush and head capable of being inclosed therein when not in use so as to maintain the brush in a clean and sanitary condition.

Another and important object of the invention consists in the provision of a handle member of novel formation having a guideway retaining the brush member in a closed position whereby the same may be securely held when in use or not in use and which also renders the device very desirable in use when traveling inasmuch as the same can be carried in the pocket or packed in a suitcase or valise without soiling the clothes.

With the above and other objects in view, the invention consists of certain combinations and arrangements of parts as will be hereinafter more fully described, claimed and illustrated in the accompanying drawings, in which:

Figure 1 is a side elevation of our improved tooth brush when not in use. Fig. 2 is a similar view but showing the brush as in use. Fig. 3 is a longitudinal sectional view of the device shown in Fig. 2. Fig. 4 is a similar view of the device as shown in Fig. 1. Fig. 5 is a cross sectional view taken on the line 5-5 of Fig. 1. Fig. 6 is a detail perspective view of the brush element removed.

As illustrated, our improved tooth brush embodies a handle 10 in the form of a hollow tube having a longitudinal slot 11 in its body, such slot terminating short of the end portions of the tube. One end of the tube is closed by an end wall 12 while the other end is open. The side wall of the tube adjacent each of the ends is thickened as clearly shown in the drawing. The side edges of the slot 11 form a pair of flanged sides or ribs 13 and in continuation of the

ribs 13 are internal ribs 14 at the forward end of the handle for receiving and holding the brush element therein. This latter element is indicated by the numeral 15 and comprises a stem formed at its free edge 60 with an enlargement 16 of substantially circular or oval cross section and conforming to the interior cross section of the tube forming the handle while the opposite longitudinal side edges of the stem are formed 65 with grooves or guideways 17 for engagement with the ribs 13 and 14 of the handle members so as to hold the brush element and head 18 securely in engagement with the handle. The enlargement 16 is preferably 70 made to fit snugly within the enlarged open end of the handle so that the brush may be readily engaged in the handle when not in use or when desired to use the brush, so that accidental displacement of the brush element is prevented. It will also be observed that the back portion of the handle is reduced in thickness adjacent to the head to provide a gripping portion, the curvature of which may be varied.

The parts are preferably constructed of hard rubber although the same may be constructed of bone or other desired material, as falls within the scope of the same as claimed.

It will thus be evident that the device can be economically produced and it will be further apparent that the device has many advantages over the ordinary tooth brush, in view of the fact that when not in use, it can be inclosed and thereby not exposed to dirt and germs, thus insuring of the same being kept absolutely clean and sanitary.

We claim:

A tooth brush comprising a tubular handle having a slot extending longitudinally thereof, a brush carrying element having grooved sides engaged by the edges of said slot and slideable with reference to the handle, and a head on said brush carrying element adapted to close the end of said handle when positioned therein.

In testimony whereof, we affix our signatures in presence of two witnesses.

PETER F. WHITE.
WALTER GRANT.
